ATTORNEYS.

UNITED STATES PATENT OFFICE.

ERNEST PAYNE, OF BINGHAMTON, NEW YORK.

PIVOTED HEADLIGHT FOR LOCOMOTIVES.

1,407,766.

Specification of Letters Patent. Patented Feb. 28, 1922.

Application filed May 20, 1921. Serial No. 471,264.

To all whom it may concern:

Be it known that I, ERNEST PAYNE, a citizen of the United States, residing at Binghamton, in the county of Broome and State 5 of New York, have invented certain new and useful Improvements in Pivoted Headlights for Locomotives, of which the following is a specification.

My invention relates to pivoted headlights 10 for locomotives. The light is automatically operated by the movement of the forward truck, so that the light will always point in the direction in which the locomotive is moving, whether rounding a curve or traveling 15 straight ahead and it has for its object to provide a pivoted headlight mechanism which can be attached to differently positioned head lights, and which at the same time can be cheaply manufactured and assembled. With these objects in view my invention consists in certain novel features of construction and arrangement of parts as will be hereinafter more particularly described and pointed out in the claim; reference being had to the accompanying drawings, in which:

Fig. 1, is a perspective view of my device, partly in cross-section as applied to a locomotive.

Fig. 2, is a perspective view of my device applied to a differently positioned headlight on a locomotive.

Fig. 3, is a plan view of my device.

Fig. 4, is a perspective view of my device, 35 partly in cross-section.

The same reference characters denote like parts in each of the several figures of the drawings.

In carrying out my invention, I provide a 40 gear frame A, which may be mounted in any convenient manner in the cross beam C, of the locomotive truck. Mounted on the inner side of the front end of frame A, I have the mesh or cogs d, adapted to receive a gear. 45 Vertically and pivotally mounted in any convenient manner on the forward platform D, of the locomotive, I have the sectional vertical shaft E, and on the lower end of which I have mounted the gear 2, so, positioned to operate in the cogs d; the sectional vertical shaft E is made up of sec-

tions 3, 4, and 5; at the base of section 3, I have mounted the gear 2; this section is slotted at its upper end by the slot e, and section 5 is slotted in its lower end by the 55 slot f; the central section 4 has projecting from the upper and lower ends thereof the lugs, 6, 6 adapted to meet and enter the slots e and f; on this sectional shaft E, I have slidably mounted the sleeves 7, 7; which 60 have mounted therein the set screws 8, 8. Mounted on the upper end of shaft E, I have the crank 9, pivotally engaging the lug 10, mounted on and projecting from the headlight box F; the headlight box F being 65 pivotally mounted on the locomotive body, by means of the pivot 11. In another form of my device, I have the brace G mounted on the front of the locomotive body and projecting the upper and lower parallel extending lugs 12, 12; the upper end of shaft E being pivotally mounted in said lugs, and mounted on said shaft, in any convenient manner and between the lugs 12, 12 I have 70 the head light box F.

In the operation of my device, the frame A, is moved to the right or left or straight ahead by the curvature of the track and the consequent turning of the truck beam C to the right or to the left, and it thus causes 80 the gear 2 to turn, which causes the shaft E to turn and through the movement of the lever, turns the headlight box F to the right or to the left, whether the box F is mounted directly upon shaft E as shown in Fig. 2 or 85 whether it is connected by a lever movement. When it is desired to open the ash door of the furnace or for any other reason to remove the shaft E, I loosen the set screws mounted in the sleeves 7, 7 and then move 90 the sleeves along said shaft until the central section 4 can be removed from the slots and thus leaving an open space in front of the boiler head. To place the shaft in use, I replace the central section 4, adjust the 95 sleeves 7, 7 and clamp the sleeves in any desired position, by means of the set screws 8, 8 and the device is ready for operation.

Having thus described my invention, what I claim as new and for which I desire Letters Patent is as follows:

In combination with a locomotive and the

forward truck thereof—a guide frame projecting longitudinally forward from the truck beam, a series of cogs mounted on the inner face of the front end of said frame, a gear meshing into said cogs, a vertical shaft pivotally mounted in the head platform of the locomotive and supporting said gear meshing into said cogs, a removable section

to said shaft, means for clamping and unclamping said section in position, a headlight box pivotally mounted on the locomotive body, pivoted lever connection between said shaft and the headlight box.

In testimony whereof I have affixed my signature.

ERNEST PAYNE.
